UNITED STATES PATENT OFFICE.

JOHN S. JUSTIN, OF NOCONA, TEXAS, ASSIGNOR TO H. J. JUSTIN AND SONS, OF NOCONA, TEXAS, A COPARTNERSHIP CONSISTING OF MRS. H. J. JUSTIN, W. E. JUSTIN, S. A. JUSTIN, J. S. JUSTIN, ENID JUSTIN STELZEE, FERN JUSTIN SENTER, ANIS JUSTIN LEMON, AND MYRL JUSTIN.

BOOT TONGUE.

Application filed February 19, 1924. Serial No. 693,759.

The present invention relates to the manufacture of boots and shoes, and has particularly to do with the patterns and shaping of the tongue portion thereof.

5 The primary objects of the invention is to produce a tongue having the same marginal shape at the ankle as the quarter and to do away with the waste incidental to the conventional preparation of tongue stock; 10 secondarily, it is an object of the invention to provide a new and better shaped boot or shoe tongue by employing an improved pattern adapted to respond readily to a crimping process whereby to give it the necessary shape; and lastly to obtain a 15 tongue of such configuration as will facilitate rapid and neat lacing of the boot with an avoidance of bunchiness and wrinkles.

These, and such other objects as may hereinafter appear, are attained by the novel construction, arrangement, and combination of elements set forth in the specification which follows and fully disclosed in the single sheet of drawing, attached hereto, and 25 made a part of this specification.

In said drawing:—

Figure 1 is a plan view of a blank form which the improved tongue is formed;

Figure 2 is a plan view of the blank 30 shown in Figure 1 after the edges of the material are stitched together;

Figure 3 is a transverse section showing the blank folded preliminary to crimping;

Figure 4 is a side elevation of a tongue 35 made in accord with the invention; and

Figure 5 is a plan view of one boot quarter showing the manner of attaching the tongue, the view of the latter being fragmentary.

Like reference characters are used to designate similar parts of the drawing and in the description which follows:

The material or stock of the tongue 10 is cut by pattern as shown in Figure 1. With the finished surface inside, the vertical edges 45 thereof, 11, are brought together and stitched to form a seam 12. A zig-zag seam closing machine serves admirably for this purpose. By so stitching, the cut out portions 13 in the upper end of the tongue 10 are 50 brought adjacent one another as disclosed in Figure 2.

The stitched tongue 10 is now folded back upon itself as disclosed in Figure 3, the seam 12 being at the front of the fold of four thicknesses of leather. In this condition, 55 the tongue 10 is placed in a crimping machine and manipulated therein until the shape disclosed in Figure 4 is obtained.

The tongue 10 is next allowed to dry, and is then ready for use. When applied to a 60 boot, the material of tongue 10 adjacent seam 12 is cut giving said tongue a marginal configuration substantially identical with that of the quarter 14 of a boot, shown in Figure 5, permitting of a snug fit at the 65 ankle thereof when secured to said quarter in the usual manner. A central crease upon the tongue 10 is also obtained, such crease urging the material of tongue 10 outward at its center whereby conformity with the 70 leg is secured during the lacing operation.

It is very material to the success of the invention that the vertical edges 11 are not overlapped. These edges must be held flat during their joinder in the zig-zag seam 75 machine and neither edge may be disposed above the other. In this manner only may even crimping be obtained for otherwise one side of the tongue 10 is crimped to a greater extent than the other, producing so bunchiness and an uneven fitting of the tongue 10 upon the quarters 14.

I claim:

As a part of an upper for a boot, a tongue having the edges thereof disposed adjacent 85 to each other and constructed and arranged to be separated by cutting a joining thread and to be secured to the edges of the quarters, said tongue preliminary to attachment to such quarters having its adjacent edges 90 secured by said thread and its body creased along three lines, there being two edge creases and a middle crease, the two edge creases extending inwardly and the middle crease outwardly, and the edges of the tongue 95 in the region of the ankle being crimped to correspond to the curvature of such quarters thereabout.

JOHN S. JUSTIN.
